CONTAINER OPENER AND SPOUT

John K. M. Harrison, Ogontz, and Walter E. Flack, Huntingdon Valley, Pa.; said Flack assignor to Container Corporation of America, Chicago, Ill., a corporation of Delaware

Application April 24, 1939, Serial No. 269,822

6 Claims. (Cl. 221—23)

This invention relates to devices useful for opening sealed containers, and also serviceable as a spout for emptying such containers wholly or in part, as desired.

5 More particularly the present invention aims to provide a simple form of such device comprising a tubular member having an abutment flange and associated aperture-forming means at one end, said means being adapted to move the displaced material away from the aperture incidental to 10 making said aperture.

Another aim of this invention is to provide a device of the type indicated in the preceding 15 paragraph which when applied to the end of a sealed container automatically holds itself in position ready for the pouring operation.

Other aims of a tributary nature will be hereinafter disclosed or become apparent from the following description of a typical embodiment 20 of this invention, as illustrated by the accompanying sheet of drawings, while the concluding claims tersely recite the features of novelty.

In the drawing:

Fig. I is a perspective view of an end portion of 25 a sealed container with the improved combination opener and spout in initial position, preparatory to forming an aperture in the end of said container.

Fig. II is a central vertical section of the same, 30 with the opener and spout applied or ready for emptying the container.

Fig. III is a vertical section, taken approximately on the plane III—III of Fig. II.

Fig. IV is a horizontal section on the plane 35 IV—IV of Fig. II.

Fig. V is a fragmentary detail section herein-after fully described; and,

Fig. VI is a perspective view showing a container with the opener and spout applied and in 40 pouring position.

In the drawing, the reference character 1 designates a suitable container for fluid, such as oil for example, said container having sealed-in ends 2 and being fabricated with a suitable impervious inner coating 3. In addition, one of 45 the ends, or both if desirable, is provided with a suitably scored and readily movable section 4 conveniently, although not essentially, of triangular contour; said section having an angular point 5 in proximity to the container body wall and the opposing base 6 in a plane at right angles to a radial line through the angular point 5.

Referring now to the novel combination opener 50 and spout of this invention, which is compre-

hensively designated 7, the same preferably comprises a tapering tubular body portion or spout 8 having at the larger end 9 an eccentrically-disposed and preferably slightly angular related discous flange 10. This flange 10 has the surrounding edge appropriately beveled outwardly at 11, for a purpose later on explained, and through the planar portion there is appropriately cut or otherwise displaced a triangular-shaped section to provide an outlet orifice 12 of a contour corresponding substantially with the outline of the container end movable section 4 above referred to. In other words, the flange 10 is provided with an approximate rectangularly-related triangular-shaped cutter 13 projecting in a direction opposed to that of the spout 8, and the base 14 of which is at right-angles to a radial line through either the apex or point 15 of said cutter, or the angular point 16 of the flange 10 caused by displacement and formation of the cutter 13. It is also to be noted that the unattached or flanking sides 17 of the cutter 13 are slightly beveled for the obvious purpose of presenting more effective edges for severing purposes, as hereafter set forth. Preferably, the device is provided with an air vent 18 located as shown, to prevent formation of a vacuum in the container during emptying thereof.

In using the opener and spout 7 for emptying oil containers 1 fabricated of paper, fiber or other suitable material with the ends retroverted and spun over inwards at 19, to seal the ends 2 in position, it is to be particularly noted the greater diameter of the eccentric flange 10 should be slightly larger than the inner diameter of the spun over retroversions 19 for the purpose later on clarified, while the smaller diameter of said flange 10 caused by formation of the bevel edge 11 should substantially be the same as that of the inner diameter above referred to. Referring first to Fig. I, it will be readily understood that the user first places the point 15 of the cutter 13 in coincidence with the apex 5 of the container end movable section 4, and the opposing bevel edge 11 of the eccentric flange 10 diametrically related and resting on the container end 2 at 20, after the manner of a slideable fulcrum. Now, it will be clearly apparent that as pressure is applied to the cutter 13, it will gradually sever or disrupt the movable section 4, with the coating 3 within its confines, and simultaneously swing said section inwardly of the container 25 together with the related coating 3 and, by sliding of the fulcrum point 20 diametrically away from the apex 5. Upon completion of the operation 30

just described, further pressure on the flange 18 will cause the larger diameter beveled edge to annularly snap and bite into the container body retroversion 19, as best indicated at 21 in Fig. V, whereby the opener and spout 1 will be firmly held in mutual engagement with the container end 2. The parts 3 and 4 are thus prevented from moving back, by contacting the confronting cutter 13, into the province of the spout orifice 12, or interfering with outflow of the container, as readily understood from Figs. II and VI.

From the foregoing it will be evident that other modes of applying the principle of this invention may be employed, changes being effected as regards the details disclosed in order to adapt said invention to other usage. It is, accordingly, to be understood the following claims are intended to cover such equivalents, of the actual showing herein, as the state of the prior art will permit.

Having thus described our invention, we claim:

1. A container opener and pouring device comprising a tubular spout with an eccentrically related flange at one end adapted for forced fitment into the spun over end of a container, and a cutter member displaced outwardly from said flange within the confines of the adjoining spout end.

2. A container opener and pouring device comprising a tubular spout with an eccentrically related discous flange at one end, said flange having the circumferential edge surroundingly beveled, and a cutter member struck outwardly from said flange within the confines of the adjoining spout end.

3. A container opener and pouring device comprising a tubular spout with an eccentrically re-

lated discous flange at one end, said flange having the circumferential edge surroundingly beveled, and a cutter member struck outwardly from said flange within the confines of the adjoining spout end, said cutter member being of triangular contour and disposed in a plane substantially at right angles to the outer face of the flange.

4. A container opener and pouring device comprising a tubular spout with an eccentrically related discous flange at one end, said flange having the circumferential edge surroundingly beveled, and a cutter member struck outwardly from said flange within the confines of the adjoining spout end, said cutter being of triangular contour with its base in a line substantially diametric of the flange with the flanking sides beveled to define inwardly active severing edges.

5. A container opener and spout device comprising a tapering tubular portion with an eccentrically-disposed and angularly-related discous flange at one end, said flange having the circumferential edge beveled to define a larger diameter facing the tubular portion, and a triangular cutter member struck outwardly from the discous flange to provide an outlet orifice therethrough, said cutter member being disposed in a plane approximately at right angles to the discous flange.

6. A container opener and spout device as defined in claim 5 wherein the flanking free edges are beveled to provide inwardly active cutter edges, and the flange surrounding bevel edge is adapted to bite into the material of the container when said device is applied thereto.
